UNITED STATES PATENT OFFICE.

JAMES WILKINSON, OF BIRMINGHAM, ALABAMA, ASSIGNOR TO THE WILKINSON STEAM TURBINE COMPANY, OF BIRMINGHAM, ALABAMA, A CORPORATION OF ALABAMA.

GOVERNING MECHANISM FOR TURBINES.

SPECIFICATION forming part of Letters Patent No. 761,865, dated June 7, 1904.

Application filed March 4, 1904. Serial No. 196,572. (No model.)

To all whom it may concern:

Be it known that I, JAMES WILKINSON, a citizen of the United States, residing at Birmingham, in the county of Jefferson and State 5 of Alabama, have invented certain new and useful Improvements in Governing Mechanism for Turbines, of which the following is a specification.

My invention relates to a fluid-pressure-governing mechanism for multiple-stage turbines, and has for its object to simplify and improve the fluid-controlling means which 10 actuate the motor-fluid valves in groups across the stages.

This invention covers an improvement in the construction of a governor-nozzle adapted to operate with a combined injector and injector effect to control the fluid-pressure in conduits leading to the valve-controlling means 15 and designed to maintain, by a full ejector action at all points of its travel, a partial or complete vacuum in the controller-chamber and conduits not subjected to its injector action.

My invention further relates to improvements in the fluid-pressure means controlling the operation of the supply and stage valves and in the construction of the diaphragms 20 with stage-valve seats disposed horizontally 25 in a peripheral shoulder whose upper surface serves as a superheating-table for the reception of steam-coils acting to evaporate the water of condensation and increase the efficiency of the motor fluid.

My invention comprises the construction and arrangement of parts hereinafter more specifically set forth and described, and illustrated in the accompanying drawings, forming a part hereof, and in which—

Figure 1 is a partial transverse vertical section through a turbine, which is shown broken away and enlarged to better illustrate the valve-controlling means. Fig. 2 is a partial sectional view taken on a vertical curved plane

45 through the row of working passages, showing the supply and stage valves in elevation and illustrating the fluid-pressure-governing mechanism. Fig. 3 is an enlarged plan view

of the governing mechanism with the nozzle-casing removed. Fig. 4 is a similarly-enlarged plan view of the nozzle-piston. Fig. 5 is a top view of the nozzle-casing looking down through the supply-port. Fig. 6 is a detail view of a detachable division-plate for the nozzles.

The same reference-numerals refer to the same parts throughout the drawings.

Inasmuch as my invention relates principally to valve controlling and actuating means and is equally applicable to turbines of different constructions, I have here illustrated only so much of a preferred type of turbine as is necessary to a clear understanding of the construction and operation of my governing means.

As shown, the turbine comprises the supply-head 1 and diaphragm 2, having a shoulder 3 and flange 4, which engages and interlocks with said head and succeeding diaphragms, being surrounded by a strengthening-shell 5 and secured therein by a shoulder and locking-strip 6 in the manner shown in my Patent No. 745,270, issued November 24, 1903. The shell is cut away to form the chamber 7, to which steam may be admitted in 65 any desirable manner.

In the head 1 I provide an annular supply-passage 8, which communicates with a suitable source of motor fluid and delivers it through branch passages 9 to the several valve-chambers 10, from the lower ends of which lead tapering passages 11, forming the supply ends of nozzles 12. These nozzles 12 are formed in an annular strip or ring 13, securely bolted to the inner face of head 1, and are subdivided 80 by one or any desired number of division-plates 14 and disposed at the proper angle to deliver the motor fluid so that it will act with the highest efficiency against the buckets 15, secured around the rotor-wheel 16. The ring 13 may, if desired, be formed by a plurality of segments.

Instead of leading the stage-nozzles directly through the shoulder 3 of the diaphragm 2, which divides the interior of the turbine into 95 wheel compartments or stages, I cause the

motor fluid from buckets 15 to pass over the shoulder 3 and through ports 17 in its inner side wall to enter stage-valve chambers 18. A plurality of compound nozzles 19, formed in a strip or ring 20, seated in a recess in the under face of the diaphragm and bolted thereto, communicate each with one of the chambers 18 and deliver the motor fluid against the buckets on a rotor-wheel 16 in the second 5 stage. Channels 21 are formed in the side walls of nozzles 19 for the reception of the removable division-plates 22, whose sides are of even thickness throughout to fit securely in said channels. The central portion or that 10 part of the plate which is utilized to direct the motor fluid is thickened at its upper end 23 when it extends beyond the side portions and is slightly curved upwardly to conform with the nozzle-passage 19. This central portion 15 tapers to an edge at the discharge end of the nozzle, so that expanding-passages are formed and designed to abstract any desired percentage of velocity from the fluid-pressure. As 20 many of these division-plates may be used as desired, and they may be secured in channels 25 21 in any approved manner.

To prevent condensation of the motor fluid to a large extent and to provide for the disposition of the water of condensation by reëvaporation, I form the superheated table on top of shoulder 3 and provide it with an annular flange 24, between which and flange 4 I coil a pipe 25, through which steam is circulated and against which the motor fluid impinges 30 after leaving buckets 15. The effect of this coil will be to maintain the temperature of the fluid in the compartment equal to or greater than the temperature of the fluid as discharged into the compartment by the revolving buckets, and by further providing the coils 26, which 35 rest upon the diaphragm, the whole compartment temperature will be maintained substantially uniform. Since this temperature will be approximately that of the fluid delivered to 40 the compartment, there will be no cooler fluid to cause condensation by commingling with the motor fluid. What condensation there is will either be caught on the superheated table and evaporated by coils 25 or will be 45 thrown off from the buckets and caught by the laminations 27, which are superheated by steam-jacket 7 and coils 25 and serve to evaporate the water of condensation caught by them. These laminations are preferably formed by 50 thin rings or annular disks separated by narrow strips 28, inserted between their outer peripheries and adapted to rest on a strip 29, which supports the bottom ring above the coils 25. The thin body portions of these 55 laminations extend inwardly to a point near the buckets 15, and since they and the interposed strips 28 are piled up until they cover the side of the wheel-compartments their flanged peripheries 28 will be securely held in 60 place by the supply-head for their compartment.

These laminations are very thin and placed so close together that the narrow spaces between them absorb the water of condensation by capillary attraction and retain it until reëvaporated. These laminae may be formed 70 in segments, so that they may be more readily inserted in place and removed from the compartment.

Within each of the chambers 10 in the supply-head I dispose a valve 30, connected by a stem 31 to a piston 32, which moves pressure-tight within the upper end of the chamber above the supply-passage 9. These chambers 10 are preferably formed as lower portions of chambers bored downwardly through the head 80 and provided with a reducing-shoulder 33, upon which rests a block 34. This block 34 constitutes the upper head for the chambers 10 and has a central cylinder 35, leading partially therethrough and connected by a passage 36 with a chamber 37. An extension 38 of the piston 32 moves pressure-tight within the cylinder 35, which is beveled at its upper end to correspond with the beveled end of the extension 38. I provide an annular recess 39 90 in the under side of the plug 34 and seat therein a spring 40, which engages the piston 32 and tends to move it toward its closed position. I provide a pressure-controller chamber formed by a casing 41, seated upon the 95 plug 34 in the chamber in the head, and by a recessed screw-plug 42, which is in screw-threaded engagement with the upper end of the said chamber, and between which in said casing 41 a circular corrugated pressure-diaphragm 43 is securely held in place. Through a passage 44 in the center of casing 41 communication is established between the chamber 37 and the controller-chamber below the diaphragm. Within the chamber 37 in the plug 100 is a controller-valve 45, having a stem 46, leading through the passage 44 and connected by bolts or in any suitable manner to the center of the diaphragm 43. The lower end of the passage 44 and the upper end of the oppositely-disposed passage 36 are beveled and form seats for the double-headed valve 45, whose 105 ends are also beveled to assist the action of the governed pressure above the diaphragm in causing the valve to move always the full 110 length of its stroke, which, it will be noted, is very short. A collar 47, secured to or formed integral with the valve 45, serves as a stop between which and the casing 41 is interposed a coil-spring 48, tending to move the valve 115 to close passage 36. A restricted passage 49 leads from the bottom of plug 34 upwardly to a passage 50, which passes at right angles thereto from the chamber 37 to a passage 51, formed by a grooved strip 52, inserted in a 120 grooved channel in the inner casing. This passage 51 leads across the stages and through the several plugs 53, which serve as heads for the cylinders 54, communicating with the stage-chambers 18. By-passages 55 lead through 125 130

the center of the plugs 53 and admit the pressure in passage 51 against the outer ends of the pistons 56, which move in the cylinders 54 and are connected by stems 57 to stage-valves 58, whose faces are beveled to engage bevel-seats 59, formed in the shoulder 3 of the diaphragm. Guides 60, integral with the inner end of each valve, direct its movements and maintain it in proper alinement with its seat, while permitting the free passage of the motor fluid from the wheel-compartment into the chamber 18. Each supply-valve 30 is provided with a tapering extension 61, which is normally disposed within the passage 11 and within which is formed a flaring central opening 62, which communicates with a passage 63, leading through the stem 31, piston 32, and the extension 38. Through the passage 36 this passage 63 will be in communication with the chamber 37, under the control of valve 45, and since the extension 38, which moves pressure-tight within the cylinder 35, is longer than the stroke of the piston 32 the pressure above said piston cannot escape through this passage 63 except through the passages 49 and 36.

My fluid-pressure-governing mechanism, which controls the admission of pressure above the diaphragms 43 in the controller-chambers, comprises a controller-casing 64 in two parts, securely bolted together and adapted to form between them a cylinder 65, within which a piston 66 is disposed and actuated by a stem 67, leading through a packing-gland 68 and connected at its outer end to any suitable governor or, if desired, manual controlling devices. A transverse opening in the shape of an ordinary keyhole 69 leads transversely through the piston and through an extension 70 thereof, which is disposed in a pressure-controller chamber 71, formed in the lower portion of the casing. Fluid-pressure is admitted to the supply-port 72 from any suitable source and passes through the opening 69, which I shall hereinafter term the "governor-nozzle," and is delivered to the passage 73 and to one or more of conduits 74, formed by superimposed channeled strips 75, seated in a shouldered groove in the supply-head and retained in position by the flange 76, formed integral with the locking-ring 6, in the manner shown and more clearly described in a pending application. The curved ends 77 of the strips 75 enter a groove in the side of a block 78, which block is screw-threaded into a chamber formed in the head 1. The passage 73 connects with a flaring passage 79, leading through the block 78, which is provided with a tongue 80, which extends flush with the top of flange 76, to which the controller-casing 64 is firmly secured. The ends of strips 75 are also flush with the top of flange 76, where they are tapered so that the openings to conduits 74 are very narrow and divided by very thin partitions. The upper end of flaring passage 79 corresponds

in width with the controller-nozzle, so that when the latter is moved fully to the left it will discharge all of the fluid stream flowing therethrough into said passage, whence it will escape through passage 73 and a nozzle 81 and 70 impinge against the buckets 15. The channels in the strips 75 terminate near their ends, where they communicate with a branch passage 82, leading through the center of the plugs 42 into the upper end of the controller-chambers above the diaphragms 43. These conduits will therefore be closed pressure-tight at their inner ends, and it therefore follows that the stream of fluid in the passage 79 will act with an ejector effect to exhaust the 80 pressure from chamber 71, and accordingly from these several conduits which open thereto. Thus when the nozzle is directly over the passage 79 all pressure will be exhausted from conduits 74 and the controller-chambers 85 above the diaphragms, and as the narrow injector portion 83 of the nozzle moves successively over the ports of the several conduits, which are shown more clearly in Fig. 3, the direct portion of the controller stream of fluid 90 will act with an injector effect to raise the pressure successively in the conduits and controller-chambers above the diaphragms to a high potential, and at the same time it will be noted that by reason of the fact that an enlarged portion of the nozzle is always over the passage 79 its full ejector effect will always exist and maintain a vacuum in the chamber 71 and in the conduits 74 not directly exposed to the injector action of the stream. It is in 100 this particular that the present construction of the controller-nozzle constitutes an improvement over the nozzles shown and described in my other pending applications. Since it will require but a small part of the 105 stream to raise the pressure in the conduits 74, it is my intention to utilize the major portion of the stream to maintain by its ejector action an effective vacuum in the controller-chamber 71. I provide for the free escape of 110 the fluid stream delivered by the injector portion 83 of the governor-nozzle to the conduits 74 after the pressure in the conduit has been raised by impact to its full potential, so that the surplus fluid will be completely ejected 115 by the flow of fluid through passage 73 and will have no effect in the conduits not directly beneath portion 83. My apparatus is designed to maintain only high pressure or a 120 vacuum and no intermediate pressures in the conduits and controller-chambers. The removable block 84 in the flange 76 permits the disengagement of the ring 6 from the shell without disturbing the plug 78 and strips 75. The motor-fluid pressure is admitted below 125 diaphragms 43 in the several controller-chambers by passages 83, leading from the supply-passage 28 through the head and side of casings 41.

The operation of my governing mechanism 130

is as follows: Before the admission of pressure to the turbine or governing mechanism the valves 30 and 45 will be moved by the action of the coiled springs bearing against them 5 to close passages 11 and 36, respectively. If pressure be turned into passage 8, it will enter chambers 10 and open valves 30 and through 10 passages 83 will act on the diaphragms 43 to lift valves 45 until they close the passages 44 and cut off the admission of the high pressure 15 into chambers 37. At the same time these valves open communication through passages 36 between passages 63, leading through the valves 30, and the passages 50 and 51, leading 20 through the casing to the stage-valve cylinders, so that the flow of the motor fluid in the nozzles 12 around the extensions 61 will act with an ejector or suction action to create a 25 vacuum in chambers 37. This partial vacuum will extend through passages 50 and 49 to the cylinders above pistons 32 and through 51 and 55 to the outer ends of cylinders 54 and will thus withdraw all pressure from above pistons 32 and by reducing the pressure against pistons 56 will assist in the opening movement of 30 the stage-valves, which will be effected by the action of the compartment-pressure against their heads 58. Before the turbine acquires 35 speed of rotation the governor-nozzle 69 will be disposed directly over passage 79, into which it will discharge the entire stream of controller fluid, which passes through nozzle 81 and assists in driving the rotor-wheels. The ejector action of this stream will produce 40 a vacuum in all the conduits 74 and in the controller-chambers above the diaphragms. As the speed of the turbine increases this nozzle 69 will move responsive to a speed of other type of governor until its injector portion 45 assumes a position over the first conduit 74. The injector action of the fluid stream will raise the pressure by impact in this conduit and in the controller-chamber to which it leads until it counterbalances the motor-fluid 50 pressure below diaphragm 43, when spring 48 will cause valve 45 to close passage 36 and open passage 44. Motor fluid will now enter chamber 37 and passing through passages 51 and 49 will equalize pressure above and below 55 piston 32, when spring 40 will close valve 30. The high pressure will continue through passage 51 and entering cylinders 54 through passages 55 will move pistons 56 inwardly against internal pressure and close stage-valves 60 58. The passage 49 being restricted will retard the movement of the supply-valve, so that it will move synchronously with the row of stage-valves. As the speed increases the nozzle 69 will successively raise the pressure 65 above the diaphragms 43 and by moving the controller-valves 45 will close supply and stage valves until the volume of motor fluid is proportioned to the load and the turbine running at a constant speed. If now the load be increased, governor-nozzle 69 will move to the

left, Fig. 2, and expose the passage leading to the diaphragm controlling the critical controller-valve 45, to the vacuum existing in chamber 70, when the pressure below the diaphragm will overcome spring 48 and raise said 70 valve to close passage 44 and open passage 36, so that the escape of the high pressure above piston 32 through passages 49, 50, 36, and 63 into the first stage will unbalance piston 32, which will be raised by the high pressure below it in chamber 10, overcoming the tension 75 of spring 40. As valve 30 leaves its seat the rush of pressure through nozzle 12 around extension 61 will act by suction in passage 63 to exhaust practically all the pressure from above piston 32 and from passage 51, so that the row of stage-valves will open automatically and the upward movement of the supply-valve be made positive. As the load is decreased toward a friction-load the controller-nozzle will successively assume a position over the conduits 74 and create pressure therein to move the controller-valves 45 to their lower positions, which will cause all the supply-valves to successively move to a closed position. Under a friction-load the controller-stream of fluid passing through nozzle 81 will not exceed a volume sufficient to drive the turbine. In case there are a large number of stages, in some of which a high vacuum exists, 95 and the ejector action of the supply-valves is not effective to lower the pressure in passages 51 below that in the last compartments springs may be utilized to assist the compartment-pres- 100 sures in opening the valves.

Though I have shown spring means to assist in closing the supply-valves 30 when substantially balanced between the pressures on both sides of their pistons this same effect may be gained by reducing the cross-sectional 105 area of the extension 38, so that the piston will be unbalanced and have a tendency to move downwardly when the high pressure exists above it.

Having thus described my invention, what 110 I claim as new, and desire to secure by Letters Patent, is—

1. In a turbine, a valve moved by a piston, a casing therefor comprising a cylinder, a controller-chamber, means to admit a high pressure to said chamber and to said cylinder below said piston, and a controller-valve movable sensitive to the pressure in said chamber which controls means to admit pressure to and eject it from above said piston. 115

2. In a turbine, a valve moved by a piston, a casing having a cylinder for said piston, a nozzle-passage for the motor fluid, a suction-passage leading through said valve and its piston and opening into said nozzle, means to 125 admit oppositely-acting pressures against said piston to substantially balance it, means acting to move the piston when balanced to close said valve, and a controller-valve which admits and cuts off pressure from above said piston 130

and opens communication between the upper end of said cylinder and said suction-passage.

3. In a turbine, a piston-operated valve controlling the admission of motor fluid to a nozzle which motor fluid acts against said piston-valve to open it, and a controller-valve which alternately admits high pressure against said piston-operated valve to close it, and exhausts said pressure into a nozzle to cause said valve to open.

4. In a turbine, a nozzle-passage, a piston-actuated valve therefor, a cylinder for said piston, an extension of said piston which moves in a chamber formed in a head of said first-mentioned cylinder, a passage leading from said chamber to a controller-valve chamber, a passage leading through said extension and piston and through a portion of said valve below its face, a permanently open conduit leading from said cylinder to said controller-valve chamber, a high-pressure passage also leading to said chamber, and valve means therein to open and close said passages.

5. In a turbine, a piston-operated valve, a cylinder therefor exposed at its lower end to a constant high pressure tending to open said valve, a nozzle-passage which is opened and closed by said valve, a conduit leading from the upper end of said cylinder to a valve-chamber which has communication by passages which lead to a source of high pressure and to said nozzle, and a controller-valve in said chamber which opens and closes said passages to vary the pressure above said piston-valve.

6. In a governing mechanism for a fluid-motor, a nozzle, a fluid-pressure-actuated valve therefor, moved in one direction by the motor fluid, a chamber for the fluid-pressure which moves said valve in an opposite direction, ports in said chamber which expose it to a high pressure and to the suction action of a passage opening into said nozzle, a controller means normally closing one or the other of said ports, and means to communicate said chamber-pressure to said valve.

7. In a governing mechanism for a fluid-motor, a plurality of piston-actuated valves, cylinders for said pistons normally exposed at one end to a high pressure, and at the other to the pressures existing in valve-chambers which severally and independently communicate with a high and a low or exhaust pressure, valves in said chambers, and fluid-pressure-controller means for said valves.

8. In a turbine, a governing means, a controller-valve actuated thereby, a three-way chamber for said valve, ways leading respectively to a high pressure, to a passage exposed to the ejector action of a stream of fluid, and to a turbine-valve-actuating means, said latter way being normally open while said other ways are alternately opened by the movement of said controller-valve, to expose said turbine-valve to a high or exhaust pressure, and

means to move said turbine-valve in opposition to said controller-pressure.

9. In a turbine, a piston-actuated valve, a cylinder therefor and a nozzle which is opened and closed thereby, a pressure acting to move said piston in one direction, a controller-valve controlling the admission of an oppositely-acting pressure to said piston, means to move said valve to a closed position when its piston is exposed to both of said pressures, a passage leading through said piston and valve which is exposed to the suction action of the motor fluid flowing through said nozzle when said valve is unseated, and to the pressure in said nozzle when said valve is seated, and through which the pressure above said piston is reduced and exhausted under the control of said controller-valve.

10. In a turbine, a piston-operated valve controlling the admission of motor fluid to a nozzle, pressure means to open said valve, a spring acting against said pressure means, and a controller-valve which alternately admits a high pressure to co-operate with said spring in closing said valve and exhausts said pressure into said nozzle to enable said first-mentioned pressure means to open said valve.

11. In a turbine, a plurality of fluid-actuated valves admitting motor fluid to a rotating element, a plurality of fluid-pressure diaphragms, actuating means under the control of said diaphragms, to operate said valves, and fluid-pressure means to move said diaphragms.

12. In a turbine, a supply-head section for a wheel-compartment, a nozzle-passage admitting motor fluid to said compartment, a fluid-actuated valve for said passage, and a valve controlling said valve-actuating fluid and operated by a fluid-pressure diaphragm.

13. In a turbine, a motor-fluid nozzle, a fluid-actuated valve therefor, means to control said actuating fluid to cause said valve to open and close, a diaphragm which operates said controlling means, and means to admit a high pressure to one side of said diaphragm and a high or low pressure to the other side to actuate said controlling means and cause the fluid-actuated valve to open or close.

14. In a turbine, a supply-head for a wheel-compartment, a chamber therein in which a fluid-actuated supply-valve, a controller-valve therefor, and a pressure-diaphragm to move said controller-valve, are disposed.

15. In a turbine, a supply-head for a wheel-compartment, a fluid-actuated supply-valve and its controller means disposed in said head, said controller means comprising a casing, a fluid-pressure diaphragm therein, and a controller-valve actuated by said diaphragm.

16. In a turbine, a wheel-compartment, a rotating element therein and a plurality of thin laminations interposed and suitably separated and disposed around the wall of said compartment for the purposes described.

17. In a turbine, a wheel-compartment, lami-

- nations disposed around the side wall for said compartment and having interstices between alternate laminations, and means to superheat said laminations.
- 5 18. In a turbine, a wheel-compartment, superimposed laminæ forming the side wall of said compartment, the alternate laminæ being of relatively narrow transverse width, and means to superheat said laminæ.
- 10 19. In a turbine, a wheel-compartment, a circumferential wall therefor provided on its inner side with a plurality of narrow interstices adapted to retain the water of condensation thrown off from the rotating element by capillary attraction, and means to reëvaporate said water of condensation.
- 15 20. In a turbine, a supply-head for a wheel-compartment, an inlet end for a nozzle formed in said head and an element securely bolted to the under side of said head and provided with a compound inclined nozzle - passage which communicates with said inlet-opening in the head and delivers motor fluid against a rotor-wheel.
- 20 21. In a turbine, a supply-head for a wheel-compartment, a plurality of openings therein communicating with a source of motor-fluid pressure and a ring secured to the under side of said head and formed with a plurality of compound nozzle-passages each of which communicates with one of said openings in the head and discharges the motor fluid at an angle against rotating buckets.
- 25 22. In a turbine, a diaphragm dividing its interior into wheel-compartments, nozzle-passages admitting motor fluid against revolving buckets in said compartments, a peripheral shoulder around said diaphragm disposed beneath said buckets and supporting superheating-coils, and valve-controlled ports for exhausting pressure from said compartments, formed in said shoulders.
- 30 23. In a multiple - stage turbine, a diaphragm-partition having a peripheral shoulder, superheating-coils disposed upon said shoulder, exhaust-ports formed in the side of said shoulder and radially - movable piston-valves which control the exhaust of pressure from said compartments.
- 35 24. In a turbine, a wheel - compartment, means to admit motor fluid thereto and exhaust it therefrom, a rotating element therein provided with peripheral buckets and actuated by said fluid, superheated side walls for said compartment, a superheating-table supporting coils disposed beneath said buckets and superheating-coils disposed upon the exhaust-head.
- 40 25. In a turbine, a divided nozzle which delivers motor fluid against a rotating element, detachable division-plates comprising a central tapering portion, and suitable recesses in the side walls of said nozzle-passages in which the sides of said plates enter and are firmly secured.
- 45 26. In a turbine, a nozzle-passage formed in a stationary portion thereof, oppositely-disposed recesses leading from its discharge end inwardly on a straight line to its curved portion, and tapering division-plates having side walls adapted to be inserted in the open ends of said recesses and secured therein. 70
- 50 27. In a turbine, fluid-pressure-controlled supply and stage valves, a controller-valve chamber for a supply-valve and one or more stage - valves, valve means in said chamber which control the admission thereto of either a high pressure or a vacuum created by the ejector action of a stream of motor fluid, and means to communicate the pressure or vacuum in said chamber to said valves. 75
- 55 28. In a turbine, fluid-pressure-controlled supply and stage valves, and a controller means for a group of said valves comprising a valve-chamber, a conduit leading therefrom and communicating with the stage valve or valves of the group and by a restricted passage with a supply - valve, and valve means to admit fluid-pressure to and exhaust it from said conduit and passage. 80
- 60 29. In a turbine, a piston-actuated valve controlling the admission of fluid - pressure through a nozzle, a cylinder for said piston, a suction-passage formed in and movable with said piston and valve, which is not directly exposed to the pressure above said piston, piston-actuated stage-valves, cylinders therefor, and means to expose said stage and supply valve cylinders to the pressure existing in said nozzle when said supply-valve is closed and to 100 the suction action created in said suction-passage by the ejector action of the fluid flowing through said nozzle when said valve is unseated, to cause said supply and stage valves to be opened by suitable means, and means to cut off communication between said cylinders and suction-passage, and to close said valves. 90
- 65 30. In a governing mechanism for a fluid-motor, a controller-chamber, a normally open passage and one or more conduits, closed at 105 their outer ends leading from said chamber, a governor - nozzle which in all positions discharges a stream of fluid directly into said passage to exhaust the pressure from said chamber by an ejector action, and which, according to its position, raises the pressure in one or more of said conduits by the injector action of part of said stream, and one or more motor-fluid valves controlled by the pressure in said conduit or conduits. 110
- 70 31. In a governing mechanism for motor-fluid valves, a controller-chamber, a passage and one or more conduits for the valve-controlling pressure leading therefrom, and a governor - nozzle movable relatively to said passage and conduit or conduits and adapted to discharge in all its positions a portion at least of the stream of fluid flowing through it directly into said passage to exhaust the pressure from said chamber. 115
- 75 120
- 80 125
- 85 130

32. In a fluid-pressure-governing means in which the injector and ejector action of a continuously-flowing stream of fluid is utilized to control means to vary the supply of motor fluid, the combination therewith of a controller-chamber, a nozzle and one or more controller-passages leading therefrom, and a governor-nozzle designed and operated to maintain a portion of its discharge end always over said nozzle-passage.

33. In a fluid-pressure-governing means, a controller-nozzle formed by a substantially keyhole-shaped opening through a movable element, and a continuously-flowing stream of fluid which is directed by said nozzle and actuates valves controlling the supply of motor fluid to a turbine.

34. In a fluid-pressure-governing means, a governor - nozzle formed with an enlarged 20 ejector and a contracted injector portion, a controller-chamber from which pressure is exhausted by the fluid flowing through said injector portion, conduits for valve controlling fluid-pressure, means to move the injector 25 portion of said nozzle successively over the ports to said conduits and valves whose operation is controlled by the pressure in said conduits.

35. In a governing mechanism for a fluid- 30 motor, an induction-nozzle, a valve therefor, motor - fluid pressure tending to move said valve in one direction, a chamber, means to maintain therein either a high pressure or a vacuum, which is created by the ejector action of a flowing stream of fluid, and means to expose said valve to said high pressure or said 35 vacuum in said chamber to control its movements.

36. In a governing mechanism for a turbine,

a plurality of turbine-valves, motor-fluid nozzles, means to move said valves in one direction, a plurality of chambers which are exposed either to a high pressure or a vacuum which is created by the ejector action of a flowing stream of fluid, and means to utilize 45 the chamber-pressures to control the operation of said valves.

37. In a turbine, a plurality of motor-fluid-supply nozzles, fluid-actuated valves therefor, plurality of secondary valves controlling the 50 operation of the turbine-valves, and a plurality of independent pressure-actuated diaphragms which actuate said secondary valves.

38. In a turbine, a plurality of motor-fluid-supply nozzles, fluid-actuated valves therefor, 55 a plurality of secondary valves controlling the operation of the turbine-valves, and a plurality of independent fluid - pressure dia- phragms which actuate said secondary valves under the control of the governor mechanism. 60

39. In a turbine operating by stage expansion, supply and stage valves for the motor fluid, fluid - pressure means to actuate said valves in groups across stages comprising conduits each of which is common to the actuating means for a group of valves, an independent controller-chamber for each conduit and a valve therein which admits a high pressure to said chamber and conduit and exhausts it therefrom under the control of a governing 65 means.

In testimony whereof I have signed my name to this specification in presence of two witnesses.

JAMES WILKINSON.
